UNITED STATES PATENT OFFICE

168,876

POWDER DISPENSING DOLL

Marguerite Adams, Manteca, Calif.

Application September 26, 1952, Serial No. 21,609

Term of patent 14 years

(Cl. D34—4)

To all whom it may concern:

Be it known that I, Marguerite Adams, a citizen of the United States, residing at Manteca, county of San Joaquin, and State of California, have invented a new, original, and ornamental Design for a Powder Dispensing Doll, of which the following is a specification, reference being had to the accompanying drawings, forming a part hereof.

Figure 1 is a front elevational view of a powder dispensing doll, showing my new design;

Figure 2 is a top plan view;

Figure 3 is a rear elevational view.

I claim:

The ornamental design for a powder dispensing doll, as shown.

MARGUERITE ADAMS.
